COMPARTMENTED ULTRASONIC PIPET WASHER-RINSER UNIT

Sherman S. Fishman, P.O. Box 321,
San Francisco, Calif. 94101

Filed May 12, 1967, Ser. No. 7,092

Term of patent 3½ years

(Cl. D16—2)

Fig. 3.Fig. 4.

FIG. 1 is an isometric view of a compartmented ultrasonic pipet washer-rinser unit, showing my new design;

FIG. 2 is a rear elevation thereof, with portions fragmentarily broken away and partially shown in cross section for clarity of illustration;

FIG. 3 is an isometric as seen from the rear of FIG. 1; and

FIG. 4 is a bottom plan view thereof.

I claim:

The ornamental design for a compartmented ultrasonic pipet washer-rinser unit, as shown and described.
